ABSTRACT: This disclosure describes a fluidic device which includes a primary supply orifice and a collector orifice with the collector orifice spaced from and generally confronting the primary supply orifice. Primary supply air is discharged from the primary supply orifice to form a primary airstream which flows into the collector orifice. To protect the primary airstream against ambient air currents, a protective fluid column at least partially surrounds the primary airstream and extends therealong to serve as a shield. The primary airstream may be disrupted or deflected in response to the presence or absence of the object which is being sensed. The presence or absence of a predetermined flow or pressure of primary air through the collector passage provides a signal indicating the presence or absence of the object.

FLUIDIC DEVICE

BACKGROUND OF THE INVENTION

In many production and manufacturing operations it becomes necessary to sense or detect the presence or absence of an object or a component thereof at various locations along the production line. Following the detection operation, it may be desirable to actuate or shut down various pieces of equipment depending upon whether or not an object is missing. For example, if an object or part is not present, it may be desirable to shut down the production equipment or to actuate other equipment which removes the faulty unit from the production line. Alternatively, it may be desirable to count the number of objects or parts and this can be accomplished by a suitable counter which adds the number of objects which are sensed.

Because of its simplicity and low cost, a fluidic sensor and fluidic system can advantageously be used to perform the sensing and related functions. In one type of fluidic sensor, a primary airstream emanates from a primary supply orifice and traverses a gap between the primary supply orifice and a collector orifice. At least some of the primary airstream enters the collector orifice to provide a signal to a fluidic control element or output device which may be responsive to either flow or pressure or the absence thereof. To accomplish the sensing or detecting function, a series of objects are passed sequentially through the primary airstream with each of the objects operating to disrupt the primary airstream and with the primary airstream automatically reestablishing itself after such object has been passed completely therethrough. Thus, as the series of objects are passed through the primary airstream, the primary airstream provides air pulses to the collector orifice, which pulses will last for a predetermined time period. This pulsed output may actuate the fluidic control element with each pulse as where the control element is a counter or a portion thereof. Alternatively, the pulses may be of such short duration that the conduit to the control element does not become sufficiently pressurized unless one of the objects is missing or incomplete in which event the pulse is of sufficient duration to actuate the output device. In this latter event, the control element may be a fluidic amplifier and the pressure of the primary air as a result of a missing object may cause actuation of removal equipment to remove the incomplete object, or shut down the production equipment, etc.

In another form of fluidic sensor, the primary airstream is disrupted by a secondary airstream and the objects are passed through the secondary airstream to deflect the latter. This type of fluidic sensor is described in applicant's copending patent application Ser. No. 742,361, entitled Fluidic Eye, and now abandoned.

Fluidic sensors of this type work very well; however, problems can arise when the sensor is used in an environment having significant ambient air currents. Such currents are not uncommon in industrial plants and may be caused, for example, by open windows in the building, ventilation fans, closely adjacent moving objects, etc. Ambient air currents of sufficient velocity and/or pressure can disrupt the primary airstream and thereby provide a false signal to the fluidic control element. Such false signal may provide false actuation of the output element and significantly upset the production operation. Furthermore, the continued presence of such ambient air currents would make the otherwise highly desirably fluidic sensing system virtually inoperative.

SUMMARY OF THE INVENTION

The present invention solves the problem of ambient air currents by providing a protective fluid layer which shields the fluid or primary air stream against deflection or disruption by ambient air currents. The protective layer should extend along the air stream on the sides thereof subject to disruption by the ambient currents. Where ambient currents may come from all sides, the protective layer is preferably in the form of a protective tubular column which surrounds the airstream and extends substantially the full length of the airstream. Although

the protective layer can be used to protect many different unconfined fluidic streams, it is particularly adapted for use with a fluidic sensor.

The present invention teaches that the protective fluid column can be formed by diverting a portion of the primary air stream adjacent the collector orifice. This can be advantageously accomplished by a deflector or diverter which is mounted adjacent the collector orifice and which reverses the direction of flow of such portion of the primary airstream and causes the latter to return toward the primary supply orifice.

In order to so deflect the portion of the primary airstream, the diverter preferably includes a concave surface which extends completely around the collector orifice. More specifically, the curved surface is preferably annular with the axis of the collector orifice coinciding with the axis of the annular surface. In axial cross section, the curved surface is concave or forms a recess which opens generally toward the primary supply orifice.

The area of the collector orifice must be sufficiently small in relation to the cross-sectional area of the primary airstream when such airstream reaches the collector orifice so that only a portion of the primary airstream will enter the collector orifice. Preferably, the central portion of the primary airstream enters the collector orifice and a peripheral region of the primary airstream is deflected by the diverter. To provide this result, the area of the collector orifice is preferably about 20 percent less than the area of the supply orifice.

The invention, both as to its organization and method of operation together with further features and advantages thereof may best be understood by reference to the following description taken in connection with the accompanying illustrative drawing.

BRIEF DESCRIPTION OF THE DRAWINGS

FIG. 1 is a semidiagrammatic top plan view of a fluidic system embodying a fluidic sensor constructed in accordance with the teachings of this invention.

FIG. 2 is a side elevational view of the sensor.

FIG. 3 is a sectional view taken along line 3-3 of FIG. 1 and illustrating the diverter on an enlarged scale.

FIG. 4 is a front elevational view of the diverter.

DESCRIPTION OF THE PREFERRED EMBODIMENT

Referring to the drawing and in particular to FIGS. 1 and 2 thereof reference numeral 11 designates a fluidic sensor constructed in accordance with the teachings of this invention. The sensor 11 includes a body member 13 which may be an integral block of plastic or other suitable material and which is suitably supported as by a supporting surface 14 (FIG. 2). The body member 13 includes block portions 15 and 17 which are preferably integrally joined by a web 19. A diverter 21 may be formed integrally with the block portion 15 or may be formed separately and affixed thereto as by a connector 23.

The body member 13 has a primary air supply passage 25 therein which terminates at one end in a primary supply orifice 27. The passage 25 is preferably generally cylindrical and the primary supply orifice 27 is preferably generally circular and of lesser diameter than the passage 25. The orifice 27, in the embodiment illustrated terminates substantially flush with an inner face 29 of the block portion 17.

The primary supply passage 25 is connected by a conduit 31 to a tank 33 or other suitable means for containing a source of primary air under pressure. The conduit 31 is releasably connected to the body member 13 by a suitable coupling 35. The pressure in the tank 33 can be maintained within prescribed limits by a pump 37. The pressure of the primary air in the passage 25 is preferably between 1 p.s.i. and 5 p.s.i. so that the air discharged from the primary supply orifice 23 will be in the form of a confined airstream or column 39.

The body member 13 also defines a collector passage 41 which terminates at one end in a collector orifice 43 with the collector orifice in the embodiment illustrated, being formed

by the diverter 21. The orifices 27 and 43 are in spaced, generally confronting relationship, and in the embodiment illustrated, these orifices as well as the passages 25 and 41 are coaxial.

A conduit 45, which may be releasably coupled to the body member 13 by a coupling 47 provides a flow path between the collector passage 41 and a fluidic control element or a fluidic output device 49. The output device 49 is a fluidic device of the type which can be actuated by the primary airstream 39 when such primary airstream is transmitted thereto via the passage 41 and the conduit 45. For example, the output device 49 may be a fluid amplifier which operates or actuates other equipment or it may be a counting device.

The primary function of the diverter 21 is to provide a protective fluid column 51 for protecting and shielding the primary airstream 39 against air currents. The diverter 21 contains the collector orifice 43 at a central location and, depending upon the axial length of the diverter 21, the collector passage 41 may also extend into the diverter in which event, the orifice 43 would only extend part of the way through the diverter. The diverter 21 may have a circular periphery as shown in FIG. 4 and a planar rear face 53 as shown in FIG. 3. The diverter has a curved surface 55 on the forward end thereof which intercepts and diverts a peripheral portion of the primary airstream 39. The surface 55 is concave as viewed in FIG. 3 and defines a recess or cavity 57 which opens generally toward the primary supply orifice 27. The curved surface 55 preferably extends completely around the collector orifice 43 and is preferably annular as viewed in front elevation (FIG. 4). The diverter 21 also has a radially narrow annular flat surface 59 the plane of which is generally perpendicular to the axis of the orifice 43.

With the primary air flowing through the primary supply orifice 27, an unconfined primary airstream 39 is directed toward the collector orifice 43 with the cross-sectional area of the primary airstream increasing as it approaches the collector orifice. The collector orifice 43 is sized so that the area thereof will be less than the cross-sectional area of the primary airstream when it reaches the collector orifice. Accordingly, a central portion of the primary airstream can enter the collector orifice 43 whereas a peripheral portion of the primary airstream 39 is directed to the curved surface 55 which reverses its direction and forms the protective column 51. As the surface 53 is generally annular in front elevation, the column 51 is also generally annular with the air therein flowing from the diverter 21 generally toward the block portion 17 and with the primary airstream 39 being generally centrally disposed within the protective column. Thus, the axes of flow of the primary airstream and the protective column extend generally in the same direction.

With this arrangement, ambient air currents are first met and themselves deflected by the protective column 51. That is, before ambient air currents can be felt by the primary airstream 39, at least some of the energy therein must first be dissipated by destruction of the protective column 51. With ambient air currents of the type normally encountered in industrial applications, such dissipation of energy renders them innocuous with respect to the primary airstream 39.

It will be apparent to those having ordinary skill in the art that the diverter concept as described herein is applicable in many instances where it is desired to protect a fluidic column against ambient or other air currents. For illustrative purposes, however, FIG. 1 shows the diverter 21 being utilized in connection with a fluidic sensor which in turn is being used to sense the presence or absence of a plurality of objects 61. The objects 61 are arranged on a suitable surface such as a conveyor 63 which moves the object 61 sequentially across the path of the primary airstream 39.

As the first of the object 61 reaches the path of the primary airstream 39, the primary airstream is disrupted so that it cannot flow into the collector orifice 43; however, when the first of the objects 61 has completely passed through the path of the primary airstream, the primary airstream quickly

reestablishes itself so that flow into the collector orifice is now possible. Thus, as each of the objects 61 moves through the path of the primary airstream, the air supply from the orifice 27 to the output element 49 is cut off. Stated differently, a pulse of air is supplied to the collector orifice 43 whenever no object is in the path of the primary airstream 39. Should one or more of the objects 61 be missing, air would be supplied to the output element 49 for a sufficient period and under sufficient pressure to actuate the output element to cause the appropriate control action to occur.

Although exemplary embodiments of the invention have been shown and described, many changes, modifications and substitutions may be made by one having ordinary skill in the art without necessarily departing from the spirit and scope of this invention.

I claim:

1. In a fluidic device for sensing the presence or absence of an object, the combination of:

a body member having first and second faces, said faces being generally confronting and spaced apart

said body member having a primary air supply passage therein connectable to a source of primary air under pressure, said primary air supply passage terminating adjacent said first face in a primary supply orifice with the primary air being discharged from the primary supply orifice in a primary airstream;

said body member having a collector passage therein, said collector passage having a collector orifice which is adjacent said second face and which is spaced from said primary supply orifice, said collector orifice being arranged to receive air from the primary airstream; and

means defining a curved surface adjacent said collector orifice and in the path of said primary airstream for diverting a portion of the primary airstream into a generally tubular protective, air column extending along and at least substantially surrounding the primary airstream to protect the latter against ambient air currents.

2. A combination as defined in claim 1 wherein said last mentioned means includes a deflector member mounted on said body member, said deflector member having said collector orifice therein and defining said curved surface.

3. A combination as defined in claim 1 wherein said last mentioned means causes the air of the protective column to flow in a direction generally opposite to the direction of air flow of the primary airstream.

4. In a fluidic system, the combination of:

means defining a primary fluid supply passage, said primary fluid supply passage defining a primary supply orifice which is capable of discharging fluid therefrom in a primary fluid stream;

means defining a collector passage, said collector passage defining a collector orifice which generally confronts said primary supply orifice and is spaced therefrom by a gap so that at least a portion of the primary fluid stream discharged from said primary supply orifice can travel across said gap to said collector orifice; and

means defining a curved surface adjacent said collector orifice and in the path of said primary fluid stream for diverting a portion of the primary fluid stream into a generally tubular, protective, fluid column extending along and at least substantially surrounding the primary fluid stream to protect the latter against ambient fluid currents.

5. A combination as defined in claim 4 wherein said curved surface surrounds the collector orifice and defines a generally annular recess opening toward said primary supply orifice.

6. In a fluidic device for sensing the presence or absence of an object and connectable to a fluidic control element, the combination of:

means defining a primary fluid supply passage terminating adjacent one end in a primary supply orifice with the primary supply orifice being capable of discharging fluid therefrom in a primary fluid stream;

means defining a collector passage connectable to the fluidic control element and terminating adjacent one end in a collector orifice, said collector orifice generally confronting said primary supply orifice and being spaced therefrom by a gap of predetermined length so that at least a portion of the primary fluid stream discharged from said primary supply orifice can traverse said gap and enter said collector orifice to provide a first signal for the fluidic control element; and

means adjacent said collector orifice for converting a portion of the primary airstream into a protective column of fluid extending along and at least partially surrounding the primary fluid stream to protect the latter against ambient air currents, disruption of the primary fluid stream for a predetermined period providing a second signal to the fluidic control element.

7. A fluidic device, comprising:

a collector having a collector passage therein, said collector passage having a collector inlet;

means including a discharge opening with the discharge opening being spaced from the collector inlet by a gap for directing a substantially unconfined fluidic stream from the discharge opening across said gap to the collector inlet; and

diverter means adjacent said collector inlet for intercepting a portion of the fluidic stream and converting at least some of said portion of the fluidic stream into a protective layer which extends along and at least partially surrounds said fluidic stream with the axis of flow of said protective layer extending generally in the same direction as the axis of flow of the fluidic stream.

8. A fluidic device as defined in claim 7 wherein said diverter means causes the fluid of the protective layer to flow in a direction generally opposite to the direction of flow of the fluidic stream.

9. A fluidic device for sensing the presence or absence of an object and connectable to a fluidic control element, said fluidic device comprising:

means defining a primary fluid supply passage terminating adjacent one end in a primary supply orifice with the primary supply orifice being capable of discharging fluid therefrom in a primary fluid stream;

means defining a collector passage connectable to the fluidic control element and terminating adjacent one end in a collector orifice, said collector orifice generally confronting said primary supply orifice and being spaced therefrom by a gap of predetermined length so that at

least a portion of the primary fluid stream discharged from said primary supply orifice can traverse said gap and enter said collector orifice to provide a first signal for the fluidic control element; and

means for converting a portion of said primary fluid stream into a protective curtain of fluid extending along at least a portion of said primary fluid stream in a direction to avoid substantial impingement against said primary fluid stream said protective curtain of fluid at least partially surrounding said fluid stream.

10. A fluidic device, comprising:

a collector having a collector passage therein, said collector passage having a collector inlet;

means including a discharge opening with the discharge opening being spaced from the collector inlet by a gap for directing a substantially unconfined fluidic stream from the discharge opening across said gap to the collector inlet; and

diverter means adjacent said collector inlet for intercepting a portion of the fluidic stream and converting at least some of said portion of the fluidic stream into a protective layer which extends along said fluidic stream with the axis of flow of said protective layer extending generally in the same direction as the axis of flow of the fluidic stream, the protective layer including a protective column extending along and substantially surrounding the fluidic stream.

11. A fluidic device, comprising:

a collector having a collector passage therein, said collector passage having a collector inlet;

means including a discharge opening with the discharge opening being spaced from the collector inlet by a gap for directing a substantially unconfined fluidic stream from the discharge opening across said gap to the collector inlet;

diverter means adjacent said collector inlet for intercepting a portion of the fluidic stream and converting at least some of said portion of the fluidic stream into a protective layer which extends along said fluidic stream with the axis of flow of said protective layer extending generally in the same direction as the axis of flow of the fluidic stream; and

a fluidic element connectable to the collector passage to receive at least a portion of the fluid of the fluidic stream from the collector passage to provide a first signal to the fluidic element, the fluidic stream being disruptable by the placement of an object therein to provide a second signal to the fluidic element.
